(57) **CLAIM**

The ornamental design for an expandable ostomy appliance,
as shown and described.

DESCRIPTION

FIG. 1 is a rear perspective view of an expandable ostomy
appliance in an expanded state embodying our new design, an
adhesive skin barrier being shown in dashed lines and forming
no part of the claimed design;

FIG. 2 is a front view thereof;

FIG. 3 is a rear view thereof;

FIG. 4 is a side view thereof as seen from the right-hand side
of FIG. 2, the opposite side being a mirror image thereof;

FIG. 5 is a bottom view thereof;

FIG. 6 is a top view thereof;

FIG. 7 is a rear perspective view of the expandable ostomy
appliance in a compacted state with its bottom portion tucked
in its top portion;

FIG. 8 is a front view of thereof in the compacted state; and,
FIG. 9 is a rear view thereof in the compacted state.

The broken line showing of an adhesive skin barrier on the
expandable ostomy appliance is included for the purpose of
illustrating environment and forms no part of the claimed
design.
